UNITED STATES PATENT OFFICE.

CHARLES E. JOHNSON, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

1,210,810.

Specification of Letters Patent.

Patented Jan. 2, 1917.

Application filed August 10, 1915. Serial No. 44,708.

To all whom it may concern:

Be it known that I, CHARLES E. JOHNSON, a citizen of the United States, and a resident of New Britain, in the county of Hartford and State of Connecticut, have invented 5 a new and Improved Lock, of which the following is a specification.

My invention relates to the class of devices above mentioned, and an object of my 10 invention, among others, is to provide a lock in which the bolt can not be moved by force applied at its ends.

One form of lock embodying my invention and in the construction and use of 15 which the objects herein set out, as well as others, may be attained, is illustrated in the accompanying drawings, in which—

Figure 1 is a perspective view of a lock embodying my invention. Fig. 2 is a view 20 of the lock case with the back plate removed, parts being broken away to show construction, and the bolt being "thrown." Fig. 3 is a like view showing the bolt partially moved and the key being shown and 25 cut in cross section. Fig. 4 is a view similar to Fig. 2, but with the bolt in its rearward position.

In the accompanying drawings the numeral 5 indicates the back plate and 6 the 30 case of my improved lock. A bolt 8 having an actuating leg 9 and a locking leg 10 is slidably mounted in the case to be actuated by the bit 11 of a key 12 that engages a notch 13 in the leg 9.

The bolt 8 is positively held against endwise sliding movement in either direction 35 so that it can not be moved until released by the key, in the construction herein shown by a lug 14 engaging within openings 15 in 40 the wall of the lock case, and this lug being preferably formed at the end of the leg 10. A spring pressing against the leg 9 forces 45 the lug 14 into the openings 15 when, in the sliding movement of the bolt, the lug reaches said openings.

In operation the bit 11 of the key moves against one of the releasing sides 17 of the notch 13, shifting the rear end of the locking

bolt and disengaging the lug 14 from one of the openings 15, as shown in Fig. 3 of the 50 drawings. The rotation of the key slides the bolt until the lug 14 arrives opposite the other opening 15 when the spring 16 shifts the bolt laterally and forces the lug 14 into the other opening 15. 55

While I have shown and described herein a satisfactory form of mechanism for accomplishing my purpose, this may be departed from to a greater or lesser degree and yet be within the spirit and intent of 60 the invention.

I claim—

1. A case, a bolt movably mounted in the case and having branching legs, said bolt projecting through an opening in the case 65 and being held against lateral movement therein, holding means carried by one of said legs to lock it against endwise movement, means to engage said holding means to coöperate in the locking operation, means 70 upon the other leg to receive a key for actuation of the bolt, and means to force said locking parts into engagement.

2. A case, a bolt movably mounted in the case and having branching legs, said bolt 75 projecting through an opening in the case and being held against lateral movement therein, means carried by one of said legs to lock it against endwise movement, means to engage said holding means to coöperate in 80 the locking operation, means carried by the other leg to receive a key to move the bolt laterally to disengage said locking means, and means similarly carried to move the bolt longitudinally. 85

3. A case, a bolt movable laterally and longitudinally within the case, legs branching from the bolt, means acting against one of said legs to force the bolt laterally in one direction, means upon the other leg to lock 90 the bolt against endwise movement in either direction, and means to engage said holding means to coöperate in the locking operation.

4. A case, a bolt slidable within the case, 95 legs branching from the bolt, one of said legs having on its inner edge a surface to be

engaged by a key to move the bolt laterally and another surface to be engaged by a key to move the bolt longitudinally, the other leg having on its outer surface a lug to engage openings in the edge wall of the case, and a spring located between the edge of

the case and the first mentioned leg to force said lug into engagement with said opening.

CHARLES E. JOHNSON.
